DESIGN FOR A FAN WHEEL GUARD

Max Weber, Chicago, Ill.

Application July 2, 1936, Serial No. 63,610

Term of patent 7 years

To all whom it may concern:

Be it known that I, Max Weber, a citizen of the United States, residing at Chicago, in the county of Cook and State of Illinois, have invented a new, original, and ornamental Design for a Fan Wheel Guard, of which the following is a specification, reference being had to the accompanying drawing, forming a part thereof.

Figure 1 of the drawing is a perspective of a fan wheel guard showing the new design; Figure 2 is a front view of the guard.

I claim:

The ornamental design for a fan wheel guard substantially as shown.

MAX WEBER.
